SETTER FOR BOWLING PINS

George Charles Debay, Woodland Hills, Calif.

Application March 17, 1950, Serial No. 150,246

3 Claims. (Cl. 273—45)

1

This invention relates to an automatic pin setting device for bowling alleys and the like. The invention herein set out may be applied to any bowling alley and also to the one set out in applicant's Patent No. 2,209,082, issued July 23, 1940.

So far as known, there has been only one or two attempts to develop a complete automatic bowling pin setter, and those which have been developed were not successful in that they lacked complete mechanical control for properly and fully removing the pin or pins when struck, or else pins were provided which did not have the proper weight and feel of regular tenpins or duckpins and thus the players soon lost interest and pleasure in playing with them.

The bowling pins employed in applicant's device have the same weight and size of regular official bowling pins and do not present any obstacle whatever toward the usual and regular playing of the modern game. When a pin is struck by a ball, in applicant's device, the pin is tossed in the usual and natural manner rearwardly or toward a side of the alley, and then it is quickly drawn below the alley completely out of the way to await resetting with the other pins that may have been knocked down. When each pin is drawn from the alley surface, a gate or plate is automatically slid into place to cover the opening and thus present a smooth flush playing surface as though the opening never existed through which the pin disappeared. By merely pressing a button at the player's end of the alley (or any other location) all the pins are reset in perfect order, that is, all the pins which have been knocked down.

One of the principal objects of this invention is to present a new and novel pin setting device which is entirely automatic and requires no attendant whatever, the means for controlling the resetting of the pins being located at any convenient place such as at the player's end of the alley or in some control room or booth; the controlling may, if desired, be operative by coins so that only a watchman-janitor may be required to keep things in order.

Other objects, advantages and features of this invention will appear from a perusal of the attached drawings, the subjoined detailed description, the preamble of these specifications, and the appended claims.

Herebelow is described one of the preferred forms of this invention in order to teach one how to make and use the same, but it is to be understood that the drawings and description

2

thereof are not to limit the invention in any sense whatsoever except as specifically limited by the appended claims.

Fig. 1 of the drawings is a plan view of a bowling alley with parts broken away, but showing the player's end and also the pin setting end,

Fig. 2 is a vertical view taken along the line 2—2 of Fig. 1, this view, however, omitting many of the structural parts of the alley and showing the control system in schematic form,

Fig. 3 is a detailed view taken along line 3—3 of Fig. 1,

Fig. 4 is a view taken along line 4—4 of Fig. 1, but showing the pin and various parts in a different position,

Fig. 5 is a plan view of a portion of the device showing a closure means to fill or plug the pin opening in the alley floor,

Fig. 6 is a longitudinal sectional view of a special valve,

Fig. 7 is a view similar to that of Fig. 6 but showing parts of the valve in a new position.

The invention can be applied to any game device wherein pins are arranged for the purpose of being struck down by one or more objects. The invention, however, is shown as in combination with a bowling alley 1 having the usual playing or ball rolling surface 2 with its side troughs 3 and 4. At the player's end 5 there is a post 6 upon which is mounted a push button controlled valve 7 for the purpose of controlling the resetting of all the pins 8 at the other end of the alley indicated at 9. The usual return track 10 is shown for the balls employed, one of which is indicated at 11.

The motivating force for all controls etc. of the invention is gas pressure in the form of compressed air which is stored under pressure in the tank indicated at 12; pipe means 13 is provided which leads to a suitable pressure controlled electric motor and pump combination (not shown) for the purpose of maintaining the air pressure. Obviously other means, such as electric and magnetic may be employed as the motivating force.

From the tank 12 extends an outlet pipe 14 which has the two branches 15 and 16; the branch 16 of which leads to a distributing block 17 from which lead a number of pipes 18 for providing a number of pin setting units with a constant pressure of air, and the branch 15 leads to a valve 7 which is under push-button control by a player and thence through the pipe 19 to an air distributing block 20 which supplies the con-

trolled air pressure to a number of operating cylinders 54.

The apparatus for each unit is mounted upon a floor 22 and some parts thereof on the subfloor 23. Each pin has its individual unit for causing the pin, when struck, to disappear through the alley floor and to reset the pin at the same time that any other pin needs setting, that is, all the struck pins are reset at the same time, if down, but the pins that may not be down are not disturbed.

Each pin setting unit includes a rod or guide standard 24 which is supported by the flanged element 25 that is screwed or bolted to the floor 22; and when the pin is beneath the playing surface of the alley, the rod is positioned within the pin 8 in its slide chamber 26 as shown in Fig. 3 of the drawings. A stop-pin 27 is provided at the top end of the slide chamber, and if desired, a coiled spring may be provided around this pin to ease the shock of the pin when it reaches its concealed position. The pin rests upon its platform or load plate 28 at all times except when tilted or thrown down upon the alley floor. While seated upon its platform, the pin maintains the valve pin 29 downwardly, and this valve pin opens or closes the small air valve 30; the valve pin includes a small spring which tends to force the valve pin upwardly at all times. The upper part of this platform has a disc 31 that is sized to neatly close the pin hole 32 in the playing floor, the top surface of the disc, when in its top position, being flush with the top surface of the playing floor. The platform is guided along its standard by the sleeve 33 which is fixed to the platform and also to the small valve 30 by a suitable bracket. Fixed to the bottom of the sleeve there is a bored element 34, the lower part of which supports and provides a bearing to accommodate the pulley wheel 35 and the upper portion provides the extended arm 36 which is to be operated by a means to be present explained.

The arm 36, just mentioned, is raised by the plunger 37 which has the piston 38 that rides in the upright cylinder 39; the base of this cylinder being fixed to the top surface of the subfloor 23. Air under pressure is supplied beneath the piston by the air line or pipe 40. When the bowling pin 8 is struck and knocked down, it does not roll away as its distance of travel is limited by the cable 41. This cable is flexible and one end is secured to the bolt 42, and the other end is secured to the pin 27 within the pin 8. So that the cable can ride freely over its pulley and its pin end made loose enough to let the pin freely fall upon the playing floor, the standard 24 is provided with an open slot along one side and this slot is indicated by the numeral 43.

The opening 32, through which the bowling pin passes, is closed by a stand-in plate 44 which is of the same size and configuration as the other plate or platform 28 so that the playing floor is not disturbed nor hazards created when the bowling pin is removed through its opening 32. The plate 44 is pivoted upon the U-frame 45 by means of the pintle 46 and each end of the pintle is urged upwardly by slanted slots and the end coiled tension springs 47 and 48 as these springs force the plate upwardly for final sealing of the opening 32. The legs of the U-frame ride along the top of a fixed guide plate 49 which is also U-shaped, and this latter plate is secured to the under surface of the playing floor 2. The lateral edges of this plate 49 have the spaced apart risers 75

50 and 51 and each has its cam portion 52 so as to cause the pintle 46 to carry the plate 44 upwardly and into placed-position as shown in the upper left portion of Fig. 3. The U-frame 45 and its plate is reciprocated, when conditions require it, by the push-pull rod 53 which is attached thereto at one end thereof, the other end of this rod being provided with a piston within the cylinder 54 in a manner similar to the piston 33 and cylinder 39. One of the air pressure lines 20' from the distributor block 20 connects with one end of the cylinder 54 via the master valve 56 and is operative for opening the opening 32 when the bowling pin 8 is about to be set upon the floor 2, that is, with its bottom flush with the floor. The other end of this cylinder 54 is connected with the air line 55.

A special valve 56 is employed in this invention and is compounded in order to serve in various ways to be explained later. This valve has a body portion with a central bore 58, one end of which is enlarged at 61 to serve as a cylinder for the piston 60. The piston is fixed to the end of a valve-rod 61, and this rod has the three reduced diameter portions 62, 63 and 64 which are recessed sufficiently to allow air to pass freely and pass through opposed ports. For sealing purposes, the ends of the valve are capped at 65 and 66, as shown. The cap 66, however, is provided with an inlet pipe 67 which is connected to the pin operable valve 30.

The steady air supply line 18, that is, one of them, connects with the ports 68 of the valve and allows air pressure to pass around the valve-rod portion 64 and thence to the port 69, the T-coupling 71 and then through pipe 70 to the top of cylinder 39, and the air pressure also passes or continues through pipe 70 and through valve 72 to make connection with pipe 55 that leads to one end of the cylinder 54. The steady air pressure pipe 18 also leads to the port 73 of the valve and around its opening 63 to the ports 74 and 75, the port 74 having connection with the pipes 76, 40 and 78; the pipe 76 makes connection with one side of the pin operated valve 30; the pipe 40 makes connection with the bottom of the cylinder 39, and the pipe 78 makes connection with the left side of cylinder 54. The port 75 is connected with the pipe 79 and thence to the pipe 67 leading into the chamber 81 of the main valve and to the left of the piston 60 thereof. The push button controlled air from the block 20 enters the port 82 and thence into the chamber 81 to the right of the piston 60. The port 83 is for exhausting the cylinder 81 on the right side of the piston. An exhaust port 84 is provided for the port 74 and another exhaust port 85 is provided for the port 69, as shown.

Operation.—Each one of the bowling pins is provided with the unit just explained. The only elements common to all units are the distributing blocks 17 and 20, the push button valve 7 and the air pressure tank 12. Obviously, any suitable means may be provided for keeping a constant air pressure in the tank 12, for instance, a motor-compressor set controlled by a pressure regulator that is associated with the tank.

When the bowling pin 8 is in its upright position upon the alley floor, as shown in Fig. 2 of the drawings, the main control valve 56 has its piston and valve rod 61 in the position shown in Fig. 7. In this valve position, air pressure is available to the pin valve 30 and air pressure is holding the piston in cylinder 54 so as to keep

the closure plate 44 away from its opening 32 while the pin 8 is on the floor 2 and held there by air pressure beneath the piston in cylinder 39. The other ends of cylinders 54 and 39 are vented through the main valve 56 and the right side of piston 80 is vented and thus ready for a quick thrust of the piston when pin 8 is knocked from its position as shown in Fig. 2; displacement of this pin opening the pin valve 30 and forcing the piston 80, like a shot, to the right hand end of the chamber 81.

When the valve 30 is opened, the main valve 56 has its valve rod 87 shifted to the new position as shown in Fig. 6. In this position, the bottom of cylinder 39 is vented through port 84 and the plate 28 drops and the cable 41 pulls the pin 8 onto its plate and they fall together, air pressure at the top of cylinder 39 via port 68 and pipe 10 forcing the rod 37 downwardly. When the plate 28 reaches its downwardmost position, the arm 36 strikes the pin of valve 72 and closes its vent but opens the passage therethrough so as to provide air pressure to the right side of the piston in cylinder 54 and thus force the plate 44 to close the floor opening 32 left by removal of the pin plate or platform 28. Obviously, the left side of the cylinder 54 is vented through the main valve port 84.

When the player desires to reset all the pins that may be down, he merely presses the button of valve 7 and this action causes air pressure to enter the chamber 81 at the right side of piston 80 so as to return the valve rod 87 to its original position as shown in Fig. 7. The left side of the piston 80 having been vented through the main valve port 84 via pipe 79 just before the left shift of the rod 87 was made, the pin 8 is thus caused to be returned to its floor position. Note, however, that the right side of the piston in cylinder 54 is vented through the valve 72 in that the pin thereof is raised and the valve closed to pressure air when the platform arm 36 is raised. Note, also, that a slow action element 89 is included in pipe 40 so that the cylinder 54 works a little earlier than the piston in cylinder 39 in order to avoid interference by the closure plate 44 when the pin is raised to floor position.

It is, of course, understood that various changes and modifications may be made in the details of form, style, design, and construction of the whole or any part of the specifically described embodiment of this invention without departing from the spirit thereof insofar as such changes and modifications are within the scope of the following claims:

I claim:

1. An automatic pin setting device for bowling alleys comprising an alley surface having the usual plurality of bowling pin spots opposite a player's end thereof; each spot consisting of a hole with a load plate therein, each load plate being sized to neatly fit into its respective hole without binding, a bowling pin normally upright on each load plate, a hole in each load plate, fluid controlled reciprocal means which moves vertically and which is attached to each plate for vertical movement, means in the reciprocal means to accommodate a cable, said cable being attached to its respective bowling pin and passing through the hole in its respective plate and along its respective reciprocal means and having its other end fixed to a portion of the device, a pulley attached to each reciprocal means and which is adapted to engage its respective cable and return its respective bowling pin to its up-

right position, a valve under and fixed to each load plate which has a valve pin that passes through a hole in its respective plate, said valve pin being urged continually upwardly through the plate by spring means, but which pin is held down by the weight of its respective bowling pin; and a stand-in plate for each hole in the floor which is sized to neatly close its respective hole and which stand-in plate is supported by horizontally reciprocal mechanism which includes guide means for directing its respective stand-in plate to and from position; a low positioned valve spaced beneath each load plate and which valve has an operative pin adapted to be actuated when the load plate is in its lowermost position, the said fluid controlled means lowering the load plate when the valve pin thereof is released and causing the stand-in plate to close the hole, and means including the low positioned valve to cause the stand-in plate to be removed from its respective hole and the load plate to rise with its respective bowling pin to a play position.

2. In an automatic pin setting device for bowling alleys and the like; a playing floor having a surface at one end thereof with bowling pin spots, a bowling pin on each spot, each spot constituting a hole through the floor which is sized to freely pass its respective bowling pin, each hole having a removable load plate to close it and which load plate is supported by a vertically reciprocal mechanism, a valve fixed to the underside of the load plate and having a reciprocal pin therein for opening and closing the valve, this pin passing through the load plate and being held down by the weight of the bowling pin, a cable attached to each bowling pin, the cable of each bowling pin passing through a bore in its respective load plate and having its other end fixed to a portion of the device, pulley means fixed to each reciprocal mechanism for engaging its respective cable and operative to return its respective bowling pin to its loading plate when the loading plate is lowered, a stand-in plate for each hole sized to close same when the load plate is removed, means for guiding and moving each stand-in plate, a low position valve spaced below each load plate and which is operated by its respective load plate when contacted, pressure means for operating the said reciprocal mechanism for raising the load plates, pressure means including a manually controlled master valve for lowering all the load plates together and forcing all displaced bowling pins to their proper upright position upon their respective load plates through action of the cables and for removing all stand-in plates from their respective holes as the load plates are returned to their normal position for playing purposes.

3. An automatic device for removing a bowling pin when forced from an upright playing position and for returning the pin to its upright playing position upon operation of a hand controlled fluid pressure means; the device including a floor with a hole therein of sufficient size to allow a bowling pin to pass therethrough, a surface plate neatly positioned in the hole with its top surface flush with the top surface of the floor, a rod means fixed to the undersurface of the surface plate and extending downwardly, a fluid cylinder having a reciprocal piston therein and the piston fixed to the bottom end of the rod means, a pin valve fixed to the surface plate having an operating pin therefor which extends upwardly through the surface plate and which

pin is adapted to be held downwardly by the weight of the bowling pin so as to keep the pin valve releasably closed, means supplying pressure fluid to one side of the pin valve and means connected to the other side of the pin valve to release the piston in the cylinder when this pin valve is opened so as to permit the surface plate to fall to a set stop position, bowling pin return cable means connected with the rod means for returning the bowling pin to the surface plate in an upright playing position when displaced, valve means having connection with the cylinder and pressure means for raising the piston in the

cylinder and the bowling pin to raised position and for keeping it there until release of the pin of the pin valve.
